UNITED STATES PATENT OFFICE.

IRVING W. HUCKINS, OF PHILADELPHIA, PENNSYLVANIA.

ENVELOP-BLANK PRINTING OR EMBOSSED MACHINE.

1,118,009.

Specification of Letters Patent. Patented Nov. 24, 1914.

Application filed May 21, 1907. Serial No. 374,951.

To all whom it may concern:

Be it known that I, IRVING W. HUCKINS, a citizen of the United States, residing in Philadelphia, Pennsylvania, have invented 5 certain improvements in Envelop-Blank Printing or Embossing Machines, of which the following is a specification.

One object of my invention is to insure the delivery of the blanks singly and in 10 proper succession to the feeding devices of the machine; another object is to arrest the operation of the feeding mechanism of the machine in the event of the non-delivery of a blank thereto; a still further object is to 15 arrest the operation of the counting mechanism under like conditions; another object is to provide for the simultaneous printing and embossing of the blank, and a final object is to insure the retention of the blank 20 rigidly in its proper position while printing and embossing of the same is being effected. These objects I attain in the manner hereinafter set forth, reference being had to the accompanying drawings, in which—

25 Figure 1 is a side elevation of the machine looking in the direction of the arrow *x*, Fig. 4; Fig. 2 is a transverse section of the machine on the line *a*—*a*, Fig. 4; Fig. 3 is an 30 end elevation of the machine looking in the direction of the arrow *y*, Fig. 4; Fig. 4 is a view of the machine partly in plan and partly in sectional plan; Fig. 5 is a perspective view of certain elements of the printing and embossing mechanism; Fig. 6 is a 35 sectional view on a larger scale of certain of the feeding devices of the machine; Fig. 7 is a perspective view of certain of the elements of the machine whereby the operation of the feeding devices is arrested on failure 40 to supply a blank thereto, and Fig. 8 is a perspective view of a nipper constituting one of the elements of the feeding mechanism.

45 In the drawing, 1—1 represent the opposite side frames of the machine which are rigidly connected and braced by means of suitable transverse girts 2 and plate 2^a, and which are provided with bearings for the various shafts carrying the operating mechanism of the machine.

50 The envelop blanks which are to be printed bear against the forward face of the transverse plate 2^a, and are normally pressed against the same by means of a follower board 3, said blanks being also supported vertically upon rails 4, each carried by arms

on a swinging shaft 5, so that said rails can be adjusted from and toward each other to accord with the length of the blanks and the shape of the lower or flap portions of the 60 same, the plate 2^a, being provided with rollers 6, preferably covered with rubber or other frictional material, which serve to prevent the descent of one side of a blank ahead of the other when its lower portion has been 65 drawn forward beyond the ends of the supporting rails and it is not otherwise supported except by the hooked arm 7 which retains the lower end of the blank until it is drawn forward by the suction device here- 70 after described.

The suction separator comprises one or more depending tubes 9 provided with nozzles at their lower ends and connected at their upper ends to a transverse tube 10 75 which is in communication, through a valved pipe connection 11, with a vacuum chamber 12, from which the air is exhausted by a pump 13, the valve plug having a rocking movement imparted to it by means of a cam 80 14 on a rotating shaft 15 so as to alternately open and close communication between the tube 10 and the vacuum chamber.

Swinging movement is imparted to the tubes 9 by means of a cam 16 (Fig. 3) on the 85 shaft 15 which is geared by means of spur wheels 19 and 20 to a shaft 21 which constitutes one of the feed shafts of the machine and is driven by a belt 22 from a pulley 23 on the primary driving shaft 24, the latter 90 shaft having fast and loose pulleys side by side, so that by shifting the driving belt power may be applied to or cut off from the machine, as desired.

The cam 16 acts upon an anti-friction 95 roller carried by an arm 25 on a shaft 26, which has another arm 27 acted upon by a coiled spring 29 which tends to maintain the anti-friction roller of the arm 25 constantly in contact with the cam 16, said shaft 26 100 being connected to one end of a transverse bar or yoke 30 which carries the depending suction tubes 9 and is suitably pivoted at its opposite end coincident with the axis of the shaft 26.

The cam 14 acts upon an anti-friction 105 roller carried by an arm 31 on the plug of the valve and the latter is so timed in respect to the cam which effects the swinging of the suction tubes 9 that when the nozzles of the latter swing forward and approach the foremost blank of the series communication will 110

be established between said nozzles and the vacuum chamber, which communication will continue while the arms are swinging backwardly, so that the lower portion of the 5 foremost blank of the series will be caught and drawn away from the others for delivery to the feeding device, communication with the vacuum chamber being cut off on or before the time that the tubes 9 complete 10 their rearward swing, so as to release the blank, whose lower edge is now in position to be caught by a nipper 32 on the intermediate one of a series of forward feed disks 33, whereby the blank is carried forwardly 15 between said disks and a plurality of small supporting disks 34, which are carried by a frame partially surrounding the outer feed disks 33 of the series.

The disks 33 are carried by the feed shaft 20 15, which has, in addition to the cams 14 and 16, another cam 35, the latter acting upon an anti-friction roller upon an arm 36 which is mounted upon a shaft 37 having, at another point in its length, an arm 39 carrying a 25 pivoted finger 40 which is forked at its upper end as shown in Fig. 4. Rising-and-falling movements will be thereby imparted to said finger 40 as the shaft 37 rocks in its bearings, and this movement is so timed 30 that, as the lower portion of the blank is drawn forwardly by the suction nozzles, the forked upper end of the finger 40 will press upon the rear face of said lower portion of the blank and thereby prevent the same 35 from swinging forwardly out of the range of the closing nipper 32, thus increasing the certainty of action of the latter and lessening the chance of failure of the feeding devices to engage the successive blanks presented thereto.

The nipper 32 operates in a recess in the central feed disk 33, and is carried by a shaft 41 mounted in bearings in the adjoining feed disks, and rocking movement of 45 said shaft, so as to cause the opening and closing movement of the nipper at the proper times in the rotation of the feed disks, is effected by mechanism well known in the art but forming no part of my present invention, and hence not necessary to be herein described.

The nipper 32 has, some distance from the rear of its forward edge, a pair of projecting pins 42 which, when the nipper is closed 55 against the feed disk, enter openings therein, these pins, by contact with the forward edge of the blank, serving to properly register the latter upon the disk and insure the subsequent presentation of the blank in accurate relation to the printing and embossing devices in order to lead to the proper placing upon the envelop of the impressions produced by said devices.

The central disk 33 has formed in it a 60 segmental groove 43 with which coöperates

a detector finger 44 carried by a shaft 45, upon which are two arms 46 and 47, the arm 46 being connected to a rod 49, which passes through one arm of a bell crank lever 50, hung to a suitable stud on one of the side frames of the machine and acting upon a coiled spring 51, interposed between said lever arm and a collar 52 on the rod, as shown in Fig. 1. The other arm of said bell crank lever 50 is acted upon by a cam 53 on the feed shaft 21, so as to impart rising-and-falling movement to the free end of the said arm, which is provided with a projecting toe 54 for the purpose herein-after described. The vibration of the lever 50 thereby causes a rocking movement of the shaft 45 tending to throw the detector finger 44 into the groove 43 of the feed disk 33, but, when a blank is being carried around by said disk, such movement of the detector finger is obstructed and the movement of the lever 50 is therefore devoted to the compression of the spring 51, but, if no envelop blank is present on the disk 33, the full upward swing of the detector finger is 85 permitted, said finger entering the groove 43. This causes the arm 47 of the shaft 45 to act through the medium of a rod 55 upon a notched trigger 56, carried by one of a pair of retainer levers 57, which are secured to a transverse shaft 59, and to move said trigger into position to engage the toe 54 of the lever 50 as the latter approaches the limit of its upward movement.

Each of the levers 57 has anti-friction 100 rollers engaging a slightly hooked portion of one of the opposite side frames 1^a which carry the bearings for the upper shaft 21^a, these side frames being pivoted to the fixed frames at 60 and being acted upon by coiled springs 61 (Figs. 1 and 3) which tend to raise them and thus elevate the upper shaft 21^a in respect to the lower feed shaft 21 when said frames 1^a are freed from the control of the retaining levers 57. As a consequence of this construction the absence of an envelop blank on the grooved feed disk 33 will cause the projection of the notched trigger 56 into the path of the toe 54 of the bell crank lever 50, and the latter part of the upward movement of said lever will therefore be transmitted to the retainer levers 57, so as to throw their anti-friction rollers out of engagement with the swinging frames 1^a and permit the lifting movement of the latter.

The upper shaft 21^a carries an embossing die 103 and a printing die or block 104, a suitable counter die 103^a, and counter block 104^a being carried by the lower shaft 21, which also has a series of feed disks 100 (see Fig. 5) the intermediate disk of the series being equipped with an appropriate nipper or nippers 101 (Fig. 2) operated so as to engage the forward edge of the blank, 130

as soon as it has been released from the control of the nipper 32 of the disk 33. Similar disks 100 may also be provided at the ends of the upper shaft 21^a if desired.

5 Bearing upon the peripheries of the disks 100 on each side of the central disk of the shaft 21 are a pair of presser disks 105, each carried by one arm of a lever 106, which is hung upon a transverse rod 107 of the machine frame and carries on its other arm an adjusting screw 109, the latter bearing upon a spring pressed socket 110 mounted on an arm 111 on the shaft 59. When, therefore, said shaft is operated so as to throw off the 10 locking levers 57 and release the frames 1^a not only will the printing surfaces of the embossing dies and printing blocks be separated from the counter dies and blocks, but the pressure upon the levers 106 will be 15 slackened or removed, and the presser disks 105 will be relieved from feeding contact with the disks 100 of the shaft 21, thereby arresting both the printing and feeding operations. At the same time that this result 20 is effected the action of the suction separator and of the counting device with which the machine is usually provided should also be stopped until the abnormal condition which led to the failure of delivery of a 25 blank to the feeding devices has been corrected, and these objects are attained in the 30 following manner:

The shaft 59, which carries the retainer levers 57, has, at one end, an arm 62, to 35 which is connected a rod 63 passing through an opening in a swivel block 64 mounted upon an arm 65 on a shaft 66 which carries a hooked latch 67 for engagement with a pin 69 on an arm 70 carried by the plug of 40 the valve which controls the vacuum connection of the suction separator, a coiled spring 71 being interposed between the swivel block 64 and a collar 72 at the outer end of the rod 63, whereby when the retainer 45 levers 57 are moved out of engagement with the swinging frames 1^a, the arm 62 will be drawn forwardly and a yielding pressure will be imparted to the latch 67 tending to 50 throw it into engagement with the pin 69 on the arm of the valve plug, and when said arm has been moved forwardly, corresponding to the closed position of the valve, the hooked forward end of the latch will engage with the pin 69 and hold the valve in 55 such closed position until the retainer levers 57 have been again moved into their retaining position, such movement causing a suitable collar on the rod 63 to lift the latch 67 out of engagement with the pin 69, and thereby permit of a further operation of the 60 valve.

The counting device 73 is actuated by a crank 74 on a shaft 75, to which rotative movement is imparted from the shaft 37 by means of an arm 76 and a rod 77 carrying a

pin 79 which engages with the teeth of a ratchet wheel 90 on the shaft 75. Pivotally mounted on said shaft 75, however, is a lever 91 and upon one arm of this lever rests the rod 77, the other arm of said lever being 70 connected by a rod 92 to an arm 93 on the shaft 59, which carries the retainer levers, whereby when the latter are thrown forwardly to release the swinging frames 1^a, the rod 77 will be lifted so as to carry its 75 pin 79 out of engagement with the teeth of the ratchet wheel 90, and thereby stop the operation of the counting mechanism until the retainer levers have been reset and the 80 operation of the machine has been resumed. 80

In order to effect adjustment of the forked upper end of the retainer finger 40 in respect to the suction nozzles, said finger is connected to a downwardly projecting arm 94, and the latter is connected, by a 85 link 95, to an arm 96 adjustably mounted on a transverse bar or shaft 97, so that by swinging said arm on the shaft in one direction or the other corresponding movement can be imparted to the forked upper end of the finger 40, the arm 96 being secured in 90 position upon the shaft 97, after any such adjustment of the same, by tightening a set screw 99, (see Fig. 6).

Whenever a blank passes between the 95 disks 100 of the shaft 21 and the presser disks 105 it will be gripped and subjected to such lateral tension that it can not be crimped or distorted by the action upon it of the embossing dies 103 and 103^a, whereby 100 the envelop has the stamp impressed upon one corner of it, a result which would be very likely to follow in the absence of such firm grip upon the blank.

Inking mechanism of any desired character may be employed for applying the ink to the embossing die and printing block of the upper shaft 21^a, and although I have shown certain mechanism for this purpose my invention is not limited thereto and no 110 specific description of the same will be necessary.

I claim:—

1. In an envelop blank embossing machine, the combination of feeding and embossing devices for the envelop blanks, a nipper on said feeding device, a suction separator for delivering the blanks in succession to the feeding device, and means for retaining the forward edge of the blank in position for engagement by the nipper of the feeding device. 115

2. The combination, in an envelop blank printing or embossing machine, of feeding devices for the blanks, a suction separator for delivering the blanks in succession to said feeding devices; said suction separator having a controlling valve, a detector operative on the failure of delivery of a blank to the feeding devices, and means under con- 120 125 130

- trōl of the detector for operating the control valve of the suction separator.
3. The combination, in an envelop blank printing or embossing machine, of feeding devices for the blanks, a suction separator for delivering the blanks in succession to said feeding devices, said suction separator having a controlling valve, a detector operative on the failure of delivery of a blank to the feeding devices, means under control of said detector for arresting the feeding operation and at the same time controlling the operation of the controlling valve of the suction separator.
- 15 4. The combination, in an envelop blank printing or embossing machine, of feeding devices for the blanks, counting mechanism therefor, a detector operative on failure of delivery of a blank to the feeding mechanism, and means under control of said detector for stopping the operation of the counting device.
- 25 5. The combination, in an envelop blank printing or embossing machine, of feeding devices for the blanks, counting mechanism therefor, a detector operative on failure of delivery of a blank to the feeding mechanism, and means under control of said detector for arresting the feeding devices and stopping the operation of the counting device.
- 35 6. The combination, in an envelop blank printing or embossing machine, of devices for feeding the blanks, a suction separator for delivering the blanks in succession to said feeding devices, counting mechanism for the blanks, a detector operative upon failure to deliver a blank to the feeding mechanism, and means under control of said detector for stopping the action of the suction separator and counting mechanism.
- 45 7. The combination, in an envelop blank printing or embossing machine, of devices for feeding the blanks, a suction separator for delivering the blanks in succession to said feeding devices, counting mechanism for the blanks, a detector operative upon failure to deliver a blank to the feeding mechanism, and means under control of said detector for arresting the operation of the feeding devices and, at the same time, stopping the action of the suction separator and counting mechanism.
- 55 8. The combination, in an envelop blank embossing machine, of feeding devices, a suction separator for delivering the blanks in succession to said feeding devices, a retainer movable in respect to said suction separator, and acting upon the forward edge of the blank to hold the same in position for engagement by the feeding mechanism, and means for changing the position of said retainer independently of its operative movement but in the direction of said movement.
9. The combination, in an envelop blank printing or embossing machine, of feeding devices for the blank, a suction separator for delivering the blanks in succession to said feeding devices, a valve controlling said suction separator, a latch for holding said valve in operative position, a detector operative on failure of delivery of the blank to the feeding devices, and means whereby said detector is caused to open and close said latch.
10. The combination, in an envelop blank printing or embossing machine, of feeding devices for the blank, a suction separator for delivering the blanks in succession to said feeding devices, a valve controlling said suction separator, a latch for holding said valve in operative position, a detector operative on failure of delivery of the blank to the feeding devices, means whereby said detector is caused to open said latch, and a yielding device through which said detector operates to close the latch.
- 15 11. The combination, in an envelop blank printing or embossing machine, of feeding devices for the blank comprising a shaft with disks thereon, presser disks co-operating therewith, spring-pressed carriers for said presser disks, a detector operative upon failure of delivery of a blank to the feeding devices, and means under control of said detector, for relieving the pressure upon said disk-carriers.
- 20 12. The combination, in an envelop blank printing or embossing machine, of blank feeding devices including a feed roll carried by pivoted members of the frame which are acted upon by springs tending to move the feed roll out of operative position, a locking device for retaining said pivoted members of the frame and holding the feed roll in operative position, a trigger carried by said locking device, a cam-actuated lever, and a detector whereby said trigger is normally held out of engagement with said cam-actuated lever, but is permitted to move into engagement therewith on failure of delivery of a blank to the feeding devices.
- 25 In testimony whereof, I have signed my name to this specification, in the presence of two subscribing witnesses.
